REVOLVER

Louis H. Palma, Nashville, Tenn.

Application December 18, 1947, Serial No. 792,491

9 Claims. (Cl. 42—59)

1

The present invention relates to new and useful improvements in revolvers having for its primary object to improve the balance of the revolver without sacrificing the long range accuracy and firing power thereof.

In a firearm of this character the range thereof is controlled by the length of the barrel and in conventional designs, with the barrel extending forwardly of the handle a considerable distance, the firearm loses its balance by reason of the added weight at its front end thereby making it more difficult to accurately fire the revolver. Accordingly it is an object of the present invention to improve the balance of the revolver by positioning the handle substantially at the center thereof and placing the cylinder rearwardly of the handle and further to position the main part of the firing mechanism directly above the handle.

A further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a longitudinal sectional view taken substantially on the line 2—2 of Figure 1.

Figure 3 is a vertical longitudinal sectional view taken on the line 3—3 of Figure 2.

Figure 4 is a transverse sectional view taken on the line 4—4 of Figure 3.

Figure 5 is a side elevational view of the trigger and the primary hammer shown in firing position.

Figure 6 is an enlarged fragmentary detail of the cam forming part of the firing mechanism for controlling the cylinder locking pin.

Figure 7 is a transverse sectional view taken on the line 7—7 of Figure 1, and

Figure 8 is a transverse sectional view taken on the line 8—8 of Figure 3.

Referring now to the drawings in detail, wherein for the purpose of illustration I have disclosed a preferred embodiment of the invention, the numeral 5 designates a barrel projecting forwardly from a stock 6, the stock having a handle 7 extending downwardly therefrom and preferably of hollow construction and provided with a removable cover plate 8.

2

A rear sight arm 9 extends rearwardly from the top of the stock 6 with a rear sight 10 carried by said arm.

5 A rod 11 is reciprocally mounted in a bushing 12 rotatably carried at the rear end of the stock 6, the rod and bushing projecting rearwardly from the stock with a cylinder 13 rotatably supported on the rear end of the bushing under the arm 9. A guard 6a extends rearwardly from the stock 6 under the cylinder. A ratchet 14 is integrally formed or suitably secured to the front end of cylinder 13.

The front end of rod 11 projects forwardly into a chamber 15 in the stock 6 in striking position by a primary hammer 16 secured to a transverse shaft 17 journaled in the side walls of the chamber. The lower end of arm 16 is formed with a shoulder 18 engaged by a lateral pin 19 at the rear end of an arm 20 pivoted to the lower rear portion of a trigger 21 which is pivoted to the stock as shown at 22 behind a trigger guard 23 and working in the front edge of chamber 15. A wire spring 24 carried by the trigger holds the arm 20 in a raised position to releasably maintain the pin 19 engaged with the shoulder 18.

25 A wire coil spring 25 suitably secured in the upper portion of chamber 15 has one end bearing against hammer 16 and is placed under tension by a forward movement of the hammer to urge the hammer in striking engagement with the front end of rod 11 when the hammer is released by pin 19 during a predetermined rearward movement of trigger 21 doing the trigger pulling action. The trigger is returned to its forward position by a coil spring 26 positioned behind the trigger.

30 The rear end of rod 11 projects into a chamber 27 in a rotatable cap 28 positioned at the rear end of cylinder 13 and integrally formed on the rear end of bushing 12, the cap being locked in position by a dove-tail shaped locking lug 29 engaging a complementary shaped groove 30 in the under side of arm 9.

35 A secondary hammer 31 in the form of a semicircular plate is pivoted in a vertical position on a transverse pin 32 in the chamber 27, the lower edge of the hammer 31 being in the path of rearward sliding movement of rod 11 and the upper edge of hammer 31 being formed with a forwardly projecting firing pin 31a working in an opening 33 in the upper front portion of cap 28 for firing a cartridge 34 in the uppermost chamber of cylinder 13.

40 A cam 35 is also secured to shaft 17 and is formed at its lower portion with a substantially

radially extending slot 36 in which the pin 19 works for rotating the cam during the forward and backward movement of pin 19 and arm 20 by trigger 21.

A pawl 37 is pivoted at one end on a pin 38 carried eccentrically at the lower portion of cam 25, the pawl extending upwardly and rearwardly in a guide passage 39 at the rear end of stock 6 for engaging ratchet 14 at the front end of cylinder 13.

The front end of cylinder 13 is formed with circumferentially spaced recesses 40 receiving the tapered rear end of a locking pin 41 slidably mounted in the rear end of stock 6. A cap 42 slidably receives the front end of pin 41 and which is also slidably carried by the stock and with its front end riding on the edge of cam 35. A coil spring 44 is positioned in the cap behind pin 41 to project the pin into one of the recesses 40. The edge of the cam is formed with a notch 43 in which the cap 42 enters to permit unlocking movement of pin 41 during a predetermined movement of cam 35 to permit rotating of the cylinder by pawl 37 and ratchet 14.

In the operation of the device the cap 28 is removed from the rear end of cylinder 13 by a partial rotation of the cap and then withdrawn rearwardly to permit loading of the cylinder with cartridges 34 and the cap replaced and locked in position by the locking lug 29, the locking of the cap placing the firing pin 31a in firing position with the uppermost cartridge and with the lower end of secondary hammer 31 in the path of rearward movement of rod 11.

The cylinder 13 is normally held in a locked position by the locking pin 41 and the initial pulling force subjected to trigger 21 will swing primary hammer 16 forwardly to place the same under tension of spring 25 and at the same time rotate cam 35 to release locking pin 41 and move pawl 37 and ratchet 14 to rotate cylinder 13 to bring a loaded cartridge into firing position. Continued rotation of cam 35 by further rearward movement of trigger 21 will cause the cam to move the locking pin 41 rearwardly into locking engagement with the cylinder and thus hold the cylinder in firing position.

This continued movement of the trigger will also move the shoulder 18 at the lower edge of hammer 16 rearwardly to a point where the shoulder is released from pin 19 thus placing the hammer under the influence of spring 25 which then forces the primary hammer 16 rearwardly to stroke the rod 11, the blow then being delivered to secondary hammer 31 which rocks the firing pin 32 forwardly for firing the cartridge.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A revolver comprising a barrel, a cylinder rotatable at the rear end of the barrel, a handle for the barrel extending downwardly therefrom at

a point forwardly of the cylinder, said cylinder counterbalancing the weight of the barrel, and firing mechanism for cartridges carried by the cylinder.

2. A revolver comprising a barrel, a cylinder rotatable at the rear end of the barrel, a handle for the barrel extending downwardly therefrom at a point forwardly of the cylinder, said cylinder counterbalancing the weight of the barrel, and firing mechanism for cartridges carried by the cylinder, and including a trigger at the front edge of the handle, a primary hammer positioned in front of the cylinder, a secondary hammer positioned rearwardly of the cylinder, and operating means for the secondary hammer actuated by the trigger through the primary hammer.

3. A revolver comprising a barrel, a cylinder rotatable at the rear end of the barrel, a handle for the barrel extending downwardly therefrom at a point forwardly of the cylinder, said cylinder counterbalancing the weight of the barrel, and firing mechanism for cartridges carried by the cylinder and including primary and secondary hammers at opposite ends of the cylinder, an operating connection between the hammers positioned axially of the cylinder, and trigger operating means for the primary hammer.

4. A revolver comprising a barrel, a cylinder rotatable at the rear end of the barrel, a handle for the barrel extending downwardly therefrom at a point forwardly of the cylinder, said cylinder counterbalancing the weight of the barrel, and firing mechanism for cartridges carried by the cylinder and including primary and secondary hammers at opposite ends of the cylinder, an operating rod slidably axially of the cylinder and transmitting motion of the primary hammer to the secondary hammer and trigger operating means for the primary hammer.

5. A revolver comprising a barrel, a cylinder rotatable at the rear end of the barrel, a handle for the barrel extending downwardly therefrom at a point forwardly of the cylinder, said cylinder counterbalancing the weight of the barrel, firing mechanism for cartridges carried by the cylinder and step by step feed means for the cylinder.

6. A revolver comprising a barrel, a cylinder rotatable at the rear end of the barrel, a handle for the barrel extending downwardly therefrom at a point forwardly of the cylinder, said cylinder counterbalancing the weight of the barrel, firing mechanism for cartridges carried by the cylinder and step by step feed means for the cylinder, said firing mechanism and said feed means being trigger actuated.

7. A revolver comprising a barrel, a cylinder rotatable at the rear end of the barrel, a handle for the barrel extending downwardly therefrom at a point forwardly of the cylinder, said cylinder counterbalancing the weight of the barrel, primary and secondary hammers at opposite ends of the cylinder, an operating connection between said hammers transmitting motion of one to the other, a step by step feed mechanism for the cylinder, and trigger actuated means for the hammers and said feed mechanism.

8. A revolver comprising a barrel, a cylinder rotatable at the rear end of the barrel, a handle for the barrel extending downwardly therefrom at a point forwardly of the cylinder, said cylinder counterbalancing the weight of the barrel, primary and secondary hammers at opposite ends of the cylinder, operating means between the hammers transmitting motion of one to the other,

a step by step feed mechanism for the cylinder, locking means for the cylinder, and trigger actuated means for the hammers, feed mechanisms and cylinder locking means.

9. A revolver comprising a barrel, a cylinder rotatable at the rear end of the barrel, a handle for the barrel extending downwardly therefrom at a point forwardly of the cylinder, said cylinder counterbalancing the weight of the barrel, primary and secondary hammers at opposite ends of the cylinder, operating means between the hammers transmitting motion of one to the other,

a step by step feed mechanism for the cylinder, locking means for the cylinder, and trigger actuated means for the hammers, feed mechanisms and cylinder locking means, said last named means including a rotatable cam in operative engagement with the locking means, and said feed mechanism including a pawl and ratchet device connecting the cam to the cylinder.
